(57) **CLAIM**

The ornamental design for a crown ornament for a bottle cap as shown and described.

DESCRIPTION

FIG. 1 is a front view of a crown ornament for a bottle cap shown in a position of use on a bottle drawn with broken lines;

FIG. 2 is a left side view of the crown ornament for a bottle cap of FIG. 1, shown removed from the bottle;

FIG. 3 is a right side view thereof;

FIG. 4 is a back view thereof;

FIG. 5 is a top view thereof;

FIG. 6 is a bottom view thereof;

FIG. 7 is an isometric view thereof; and,

FIG. 8 is a bottom axonometric view thereof.

The broken lines in FIG. 1 illustrating a bottle depict environment and form no part of the claimed design. The broken lines in FIGS. 6 and 8 show portions of a crown ornament for a bottle cap that form no part thereof.

1 Claim, 8 Drawing Sheets
